UNITED STATES PATENT OFFICE.

OSCAR J. W. GAEBE, OF ADDIEVILLE, ILLINOIS.

AUTOMATICALLY-OPERATING CONTROL SWITCH FOR A WATER SYSTEM.

1,405,200.

Specification of Letters Patent. Patented Jan. 31, 1922.

Application filed February 6, 1918. Serial No. 215,662.

To all whom it may concern:

Be it known that I, OSCAR J. W. GAEBE, a citizen of the United States, residing at Addieville, in the county of Washington 5 and State of Illinois, have invented certain new and useful Improvements in an Automatically-Operating Control Switch for a Water System, of which the following is a specification.

10 This invention relates to a water pumping device and has for its object the production of a simple and efficient means for automatically operating a supply pump, when the water within a tank falls below the pre-
15 determined level.

Another object of this invention is the production of a simple and efficient circuit closing means for automatically closing an electric circuit through an operating motor 20 when the water within a tank falls below the predetermined level.

With these and other objects in view this invention consists of certain novel constructions, combinations and arrangements of 25 parts as will be hereinafter fully described and claimed.

In the drawings:—

Figure 1 is a side elevation of the pumping system, the electrical wiring being 30 shown in diagram,

Figure 2 is a vertical section through the water tank showing the circuit closing device carried thereby,

Figure 3 is a section taken on line 3—3 of 35 Figure 2,

By referring to the drawings, it will be seen that 1 designates the main tank to which is connected an auxiliary tank 3 and a second tank 4 by means of the supply pipes 40 5 and 6. A pump 2 is placed adjacent the main tank 1 and a pipe 7 is connected to this pump 2 and overhangs the upper end of the main tank 1 as shown in Figure 1 for the purpose of supplying water to the main 45 tank 1 from the pump 2. A main supply pipe 8 is connected to the pump 2 as shown clearly in Figure 1 of the drawing.

A motor 9 is placed to one side of the pump 2 and is connected therewith by 50 means of a shaft 10 for the purpose of driving the pump 2 as the motor 9 is operated.

The main tank 1 is provided with a laterally extending neck or pipe 11 which terminates in an upwardly extending end 12.

55 An insulated float 13 is mounted within the upwardly extending end 12 of the neck or

pipe 11 and a coil spring 14 is mounted within the upper end 12 and engages the top of the float 13 for urging the same downwardly. A plurality of contact points 15 are carried by this float 13 and are connected to the respective wires 16 and 17, the wires 16 and 17 being connected to the contact points 18 of the contact switch 19. Suitable supply wires 20 are connected to the switch 19 for the purpose of supplying current to the switch from a source of electrical supply. Suitable contact points 21 are carried by the contact switch 19 and wires 22 and 23 are connected to these contact points 21, the wires 22 and 23 being connected to the wires 24 and 25, which wires 24 and 25 are electrically connected with the motor 9. It should be understood that the contact switch 19 is adapted to merely 75 permit the electric circuit to the motor 9 to be manually closed when it is so desired, independently of the automatic switch above described. It of course should be understood that this electrical connection may be 80 arranged in the ordinary manner wherein a contact switch is used.

The pipe or neck 11 carries an insulated block 26 which block carries a plurality of contact points 27, these contact points 27 being electrically connected to the wires 24 and 25. The upwardly extending end 12 is preferably square in cross section for the purpose of holding the contact points 15 in a proper position to engage the contact 90 points 27, the float 13 also being square and fitting snugly within the upwardly extending end 12.

The contact points 15 are positioned in the inner ends of the sockets 15' formed in 95 the float 13, in order to prevent the closing of a circuit between the contacts 15 and 27 by the liquid placed within the tank 1. When the liquid within the tank 1 falls below a predetermined point, the float will drop and 100 the contact points 15 will close a circuit with the upper ends of these contact points 27 working in the sockets 15'.

As shown in Figure 1, the tank 4 may be supported upon the supporting block 28 in 105 order that the tank 4 may be supported at a proper elevation. It should be also understood that the top of all of the tanks 1, 3, and 4 are arranged on the same level in order to prevent one tank from overflowing as 110 the other tank is being filled.

As shown in Figure 2 of the drawings, the

contact points 27 are provided with an insulating coating 15^a to prevent the short circuiting through the medium of the liquid contained within the tank, but the upper 5 ends of these points 27 are left bare so as to contact with the contact points 15 carried by the plate which is supported by the float 13. These contact points 27 are also insulated from the neck 11 and suitable 10 conducting wires 24 and 25 are connected to the points 27 as shown in Fig. 2.

The operation of the device is as follows:—

Should the water within the tank 1 fall 15 below the top face of the pipe 11, the coil spring 14 will shove or move the float 13 downwardly thereby forcing the contact pins 15 in engagement with the contact pins 27 for closing a circuit therethrough and operating the motor 9. As soon as the tank 1 is 20 filled, the float 12 will be raised for moving the pins 15 out of engagement with the pins 27, and in this way breaking the electrical circuit and discontinuing the operation of 25 the motor 9.

Should it be desired to empty the tank, for the purpose of cleaning or repairing the same, a suitable pipe or hose may be inserted in the tank 1 and suitable means attached 30 thereto for drawing the water from the tank.

From the foregoing description it will be seen that a very simple and efficient device has been produced for permitting the drinking tanks 3 and 4 to be automatically filled and kept in a substantially filled condition, 35 through the operation of the automatic circuit closing means illustrated and described.

What is claimed is:—

A switch for use in connection with water systems comprising a casing, a lower insulating supporting block mounted within said casing, a plurality of contact pins supported upon said block and provided with upper contact ends, a float mounted within said casing and provided with sockets formed 45 therein for receiving at all times the upper ends of said contact pins, depending contact points fitting within said sockets formed in said float and adapted to form a contact with the upper ends of said contact pins, and a spring interposed between the upper end of said casing and the top of said float 50 for normally urging the same downwardly to an operative position.

In testimony whereof I affix my signature 55 in presence of two witnesses.

OSCAR J. W. GAEBE.
